(73) Assignee: **SmithKline Beecham Corporation, Research Triangle Park, NC (US)**

Primary Examiner—Ian Simmons

(74) Attorney, Agent, or Firm: James P. Riek

(**) Term: **14 Years**

(57) CLAIM

(21) Appl. No.: **29/137,641**

The ornamental design for an inhalation device, as shown and described.

(22) Filed: **Feb. 26, 2001**

DESCRIPTION

(30) Foreign Application Priority Data

Aug. 26, 2000 (GB) 2095346

FIG. 1 is a front perspective view of the inhalation device of our new design;

(51) LOC (7) Cl. **29-02**

(52) U.S. Cl. **D24/110**

(58) Field of Search D24/110; 128/200.23, 128/203.12, 200.12, 200.21, 200.14, 203.15

FIG. 2 is a side view; and,

FIG. 3 is a rear view.
